CLAIM

The ornamental design for a power adapter, as shown and described.

DESCRIPTION

FIG. 1 is a top front left perspective view of a power adapter showing our new design;

FIG. 2 is a top view thereof;

FIG. 3 is a top front right perspective view thereof;

FIG. 4 is a rear view thereof;

FIG. 5 is a left side view thereof;

FIG. 6 is a front view thereof;

FIG. 7 is a right side view thereof;

FIG. 8 is a bottom left perspective view thereof; and

FIG. 9 is a bottom view thereof;

FIG. 10 is a top front left perspective view of the power adapter shown in a second configuration;

FIG. 11 is a top view thereof;

FIG. 12 is a top front right perspective view thereof;

FIG. 13 is a rear view thereof;

FIG. 14 is a left side view thereof;

FIG. 15 is a front view thereof;

FIG. 16 is a right side view thereof;

FIG. 17 is a bottom view thereof; and,

FIG. 18 is a bottom left perspective view thereof.
